UNITED STATES PATENT OFFICE.

ALFRED CRAWFORD, OF NEW BRUNSWICK, NEW JERSEY, ASSIGNOR TO CRAWFORD MANUFACTURING COMPANY, OF NEW BRUNSWICK, NEW JERSEY, A CORPORATION OF NEW JERSEY.

STOP MOTION FOR KNITTING MACHINES.

Application filed November 23, 1926. Serial No. 150,293.

My invention relates to stop motions for knitting machines, and especially to the type of stop motions shown and described in United States Letters Patent, of Frank 5 Crawford, Sr., No. 1,621,397, dated March 15, 1927, on which my present invention constitutes an improvement.

The principal object of my present invention is to add, to the mechanism disclosed in the above mentioned application, restricting mechanism for preventing the drop wires of the stop motion from operating the tripping mechanism of the stop motion when the knitting machine is stopped by shifting the driving belt of the knitting machine from the tight to the loose pulley thereof, and to provide mechanism for controlling the restricting mechanism at all times directly from the belt shifter, so that the stop motion 20 may become effective as soon as the knitting machine is again set in motion.

My invention is clearly illustrated in the accompanying drawings, of which:

Fig. 1 is a plan view of a portion of a 25 stop motion showing the trip mechanism thereof, and my additional restricting mechanism applied thereto;

Fig. 2 is an enlarged plan view similar to Fig. 1;

Fig. 3 is a sectional elevation taken on the line 3—3 of Fig. 2;

Fig. 4 is a sectional elevation taken on the line 4—4 of Fig. 2;

Fig. 5 is a sectional elevation taken on the line 5—5, Fig. 3;

Figs. 6 and 7 illustrate different positions of the restraining mechanism relative to certain elements of the trip mechanism of the stop motion;

Fig. 8 is an elevation of one form of control mechanism for the restraining mechanism as applied to a knitting machine of the revolving head type;

Fig. 9 is a sectional plan view taken on the line 9—9 of Fig. 8;

Fig. 10 is a fragmentary plan view of certain of the elements shown in Fig. 9, illustrated in different relative positions;

Fig. 11 is a sectional elevation taken on the line 11—11 of Fig. 9;

Fig. 12 is an elevation of another form of control mechanism for the restraining mechanism as applied to a non-revolving head type of knitting machine;

Fig. 13 is a sectional plan view taken on the line 13—13 of Fig. 12;

Fig. 14 is an elevation of a modified form of control mechanism for the restraining mechanism as applied to a revolving head type of knitting machine;

Fig. 15 is a sectional plan view taken on the line 15—15 of Fig. 14;

Fig. 16 is a face view of a detail of the mechanism shown in Figs. 14 and 15;

Fig. 17 is a plan view of another modified form of the invention;

Fig. 18 is a detailed perspective view of a portion of the mechanism shown in Fig. 17.

My invention is applicable to knitting machines such as those illustrated in Figs. 8, 12 and 14. The machine of the rotating or revolving head type, shown in Figs. 8 and 14 comprise, in brief, a stationary frame 1 having a cylinder 2 secured thereto, and a cam ring 3 which revolves on the frame and

cylinder 2. Secured to a portion of the cam ring 3 which lies flush with the top of the stationary frame 1 is a series of upright studs 4, 4 which support a spider 5. The spider 5 supports a vertical central standard

6 on which is secured a bobbin rack 7, an upper stop motion 8 and a lower stop motion 9. The two said stop motions are connected together and operate in a manner clearly set forth in the above mentioned application, therefore, the description of the elements of these stop motions and their operation will, in the present instance, be limited to those immediately co-operating with and controlled by the elements constituting

the subject of my invention.

The lower stop motion comprises a hollow annular casing 10 having arms 11 extending radially therefrom. Each arm 11 pivotally supports a drop wire 12. The drop

wires each operate a rod 13 which extends into the hollow annular casing 10, and has a finger 14 adapted to engage a floating ring 15 which operates the trip mechanism

of the stop motion.

The annular casing 10 is provided with an enlarged circular chamber 16 which houses the trip mechanism. The trip mechanism

comprises a central spindle 17 which is directly connected to the mechanism which

actually effects the stopping of the knitting machine when a thread breaks and releases

one of the trip wires 12. This mechanism

is not illustrated as it forms no part of the present invention. A partial rotation of the spindle 17 in anti-clockwise direction, under the influence of a spring (not shown), is sufficient to effect the stopping of the machine, when any one of the drop wires 12 is released by the thread that normally engages it and by the tension thereon maintains it in a vertical position while the machine is running.

The trip mechanism is "set" by turning the spindle in a clockwise direction, and the spindle 17 is maintained in its "set" position against the action of the said spring in the following manner: Secured to the spindle 17 is a cam disc 18, on which is rotatably mounted a roller 19 adapted to a slot 20 in a holding lever 21, which is pivoted at 22 to the base of the chamber 16. The free end 20 of the holding lever 21 has a roller 23 rotatably mounted thereon which rides in a slot 24 in a latch 25. The latch 25 is pivoted to the base of the chamber 16 at 26, and has a shoulder 27 adapted to be engaged by a catch 28. The catch 28 is pivoted at 29 to the base of the chamber 16, and has an arm 30 engaged by a lug 31 on a trip lever 32. The trip lever 32 is pivoted on a pin 17* extending vertically from the spindle 17. The trip lever 32 is engaged by a knocker arm 33 extending laterally from the ring 15.

Under normal operating conditions, the tension on the knitting thread α (Fig. 4) supports the drop wires 12 in the running position, illustrated at a in said figure, the ring 15 floats freely in the annular casing 10 (see Fig. 6), the catch 28 engages the shoulder 27 and thereby holds the latch 25 against movement. The latch 25 prevents movement of the holding lever 21, which in turn keeps the cam 18 and spindle 17 from rotating.

When a thread breaks or becomes slack, the drop wire 12 moves to position b (Fig. 4) and in so doing turns the rod 13 which, through the finger 14, moves the ring 15 in the direction of the arrow α , whereby the knocker arm 33 thereon engages the trip lever 32, thereby moving the catch 28 to release the latch 25. Release of the latch 25 permits the holding lever 21 to release the cam 18 and the spindle 17, all under the power of the spring thereof, thus effecting the stoppage of the knitting machine.

When the spindle 17 and the cam 18 turn to stop the machine a rise 35 on the cam engages a roller 36 on a push back lever 37, which is pivoted at 38 to the base of the chamber 16 and has a lug 39 which engages a depending projection 40 on the ring 15, and moves the ring in a direction opposite to the arrow α . Movement of the ring in this direction reacts through the finger 14 and rods 13 to move the drop wires 12 from

the trip position b to the threading position c (Fig. 4), in which they are held by a retaining hook 41, which engages the ring projection 40.

The retaining hook 41 is pivoted on a pin 78 42 in the base of the chamber 16, and is moved into engagement with the ring projection 40 by a lug 43 on a spring pressed retaining lever 44 which is pivoted to the base of the chamber 16 at 45. The retaining lever 44 has a roller 46 which rides the high periphery of the cam 18 when the mechanism is "set" and which moves into a depression 47 in the cam 18 when the mechanism is "tripped", thus allowing the retaining lever 44 to act under the influence of its spring to move the retaining hook 41 into engagement with the ring projection 40. When the mechanism is "set" the retaining hook 41 is disengaged from the ring projection 40 by a release finger 47 on a hand plate 48 which is pivoted at 49 to the base of the chamber 16. The release finger 47 engages a lug 50 on the retaining hook 41. The release hand 48 has a pair of vertical fingers 51, 51 which are engaged by a crank pin 52 extending from a disc 53 secured to a control shaft 54. The control shaft 54 is journaled in the cover 55 of the annular casing 10, and is connected to the belt shifter of the knitting machine as will be hereinafter more fully described. The retaining hook 41 is held in engagement with the ring projection 40, to hold the ring against rotation after the retaining lever moves to release it, by a light spring 56.

After the mechanism has been tripped, it is necessary to "reset" the mechanism, as above described, before the knitting machine can again be set into motion. After the "resetting" and before the belt shifter is operated to move the belt from the loose to the tight pulley, the trip mechanism is held against tripping by the retaining hook 41, which is not released until the belt shifter 110 has been operated. By the operation of the belt shifter, the control shaft 54 is rotated and the crank pin 52 thereon turns the release hand and the finger 47 thereon moves the retaining hook 41 from the position 115 shown in Fig. 1 to the release position shown in Fig. 6, after which the drop wires move from the threading position c to the running position b (Fig. 4).

Should the operator, for any reason, have 120 occasion to stop the machine by manually moving the belt shifter, the threads α would immediately become slack and the drop wires 12 would move from the running position a to the trip position b thereby tripping the stop motion which the operator would have to "reset" before he could again start the knitting machine. Movement of the belt shifter to the "off" position turns the release hand 48 which permits the re- 125 130

taining hook to turn under the influence of its spring 56, but due to the fact that the ring 15 has moved slightly, by movement of the drop wires from the threading position to the running position, the projection 41 thereon has moved a distance which causes the point of the retaining hook 41 to strike the side of the ring projection 40 (see Fig. 7), and thereby permit the mechanism to be tripped by the ring subsequently moving when the threads become slack.

I have overcome the above described objectionable actuation of the trip mechanism by providing a second hook 60, which I term a restraining hook and which I pivotally mount on the pin 42. The restraining hook 60 is constructed in the same manner as the retaining hook 41, with the exception that the shoulder 61 thereof is formed a slightly greater distance from the pivotal centre 42 than the corresponding shoulder 62 of the retaining hook 41 (see Figs. 1, 2, 6 and 7). By so forming the shoulders 61 and 62, the shoulder 62 of the retaining hook 41 holds the ring 15 when the trip mechanism is "reset" and before the belt shifter has been moved to start the machine (see Fig. 1), whereas the shoulder 61 of the restraining hook 60 engages the ring projection 40 when the belt shifter has been moved manually to stop the machine for reasons other than a broken thread (see Fig. 7). The restraining hook 60 is under control of a spring 63 for movement in one direction to engage the ring projection and under the control of the release finger 47 which engages a lug 64 on the hook 60. The hooks 41 and 60 are actuated in the same general manner one to the other, by the release hand 48 under control of the control shaft 54.

It is desirable to maintain an operative inter-connection between the control shaft 54 and the belt shifter in order that the stop motion may become effective immediately after the knitting machine is set in motion, and in Figs. 8, 9, 10 and 11, I have illustrated the preferred form of mechanism for maintaining such interconnection on a knitting machine of the revolving head type.

The control shaft 54 is provided at its outer end with a crank 70 having a crank pin 71 which is engaged by a forked projection 72 formed on a ring 73. The ring 73 is adapted to oscillate on a second ring 74 having an annular step formation as shown in Fig. 11. The fixed step ring 74 is secured to the spider studs 4, in the present instance as shown in said figure. The oscillating ring 73 is mounted on the tread 75 of the ring 74, and is circularly guided in its oscillation by the riser 76 of said step ring 74. The top of the step ring 74 and the top of the oscillating ring 73 lie flush in a horizontal plane. On the top of the step

ring 74, I mount a series of bell-crank levers 77 pivoted at 78 thereto. Each bell-crank lever 77 is provided with a slot 79 for the accommodation of a pin 80 which projects vertically therethrough from the top 70 of the oscillating ring 73. The free end 81 of each of the bell-cranks is formed with an arcuate edge 82.

The knitting machine has a main drive shaft 85 on which is mounted a tight pulley 86 and a loose pulley 87. A driving belt 88 is adapted to be shifted from one to the other of these pulleys by a belt shifter 89. The belt shifter 89 is pivoted to the frame of the machine, and has a forked end 80 adapted to engage the belt in the usual manner. A shift rod 90 is slidably mounted in the frame, and is pivoted at one end to the belt shifter and at the other end to a lever 91 pivoted to the frame of the machine. The opposite end of the lever 91 has a slotted link 92 pivoted thereon, the opposite slotted end of which engages a pin 93 on a lever 94 mounted on the lower end of a vertical shaft 95 which is pivotally mounted in a bracket 96 secured to the frame of the machine. On the upper end of the shaft 95 is secured a presser shoe 97 which has an arcuate edge 98 which is adapted to engage the arcuate edges 82 of the bell-crank levers 77.

As shown in Figs. 1 and 9, the trip mechanism in the chamber 16 of the annular casing 9 has been set and the retaining hook 41 is holding the ring 15, and thereby the drop wires 12 are retained in their threading positions. The belt 88 is on the loose pulley 87. By moving the belt shifter 89, to move the belt 88 onto the tight pulley 86 to start the machine, the shift rod 90 will 105 be moved longitudinally against the action of the shift spring 99, in which position the shift rod 90 and belt shifter 89 will be maintained by locking mechanism (not shown) which is under direct control of the trip 110 spindle 17 of the stop motion.

Longitudinal movement of the shift rod 90 turns the lever 91 on its pivot, thereby sliding the slot of the link 92 on the pin 93, and subsequently turning the lever 94, shaft 95 and presser shoe 97 into the position shown in Fig. 10, wherein the bell-crank levers 77 have been turned on their pivots, the ring 73 has been oscillated on the step ring 74, by a spring 100 and the control shaft 54 has been turned in a clockwise direction, which, through the hand plate 48 has moved the hooks 41 and 60 into the position shown in Fig. 6, and the trip ring 15 has been released to function in its 125 normal manner as above described.

If the operator should again shift the belt 88 to the loose pulley 87, the order of operation just described would be reversed and the control rod 54 thereby turned in 130

an anti-clockwise direction to release the hooks 41 and 60 which would move, under the influence of their respective springs, to the positions shown in Fig. 7, the point of the retaining hook 41 striking the edge of the ring projection 40, and the restraining hook 60 engaging the ring projection to prevent the actuation of the trip mechanism as above described.

- 10 Upon referring to Figs. 9 and 10, it will be noted that despite the rotation of the rings 73 and 74 with the knitting head of the machine and relative to the presser shoe 97 an operative connection is established between the control shaft 54 and the belt shifter 89 immediately upon moving said belt shifter to stop the machine, to release the hooks 41 and 60 and permit them to move to their ring holding positions, and 20 when the belt shifter moves the belt to the tight pulley the said connection is immediately broken and the ring 73 is oscillated in an opposite direction on the step ring 74 by the spring 100 (Fig. 9) to turn the control rod 54 in a clockwise direction to move the hooks 41 and 60 to their ring releasing positions, as above described.

It will be understood that in event of a broken or slack thread, the belt shifting operation is subsequent to the tripping operation, wherein the ring 15 acts to trip the stop motion and the cam 18 is thereby turned to return the ring 15 and thereby drop wires 12 to the threading position, wherein the retaining hook 41 functions in holding the ring 15.

In Figs. 12 and 13, the stop motion is shown as being applied to a knitting machine of the non-rotating head type, and in which the annular casing 10 remains stationary. The control rod 54, in this instance, is applied with the crank 70, and the crank pin 71 thereof is engaged by a slotted lever 101 secured to a radial shaft 102 rotatably mounted in a bracket 96 secured to the frame of the machine. On the radial shaft 102 is a second lever 103 which is engaged by a slotted lever 104 on the upper end of the vertical shaft 95^a. The shaft 95^a is equipped with a lever 94^a connected by a slotted link 92^a with a lever 91^a pivoted on the frame of the machine. The lever 91^a is connected by a link 90^a with the belt shifter 89^a.

55 Movement of the belt shifter to the tight position, through the train of links and levers above described, rotates the control shaft 54 in a clockwise direction and movement of the shifter to the loose position rotates the control shaft 54 in a counter-clockwise direction, for the purpose hereinabove described.

As shown in Figs. 14 and 15, the stop motion is applied to a rotating head type of 65 knitting machine, and the interconnecting

mechanism between the control shaft 54 and the belt shifter 89 is shown in a modified form, the interconnection being of an intermittent nature. In this instance, the rings 73 and 74 are replaced by a series of 70 yoke heads 105, spaced around the machine, which are adapted to be engaged by an arrow head 106 secured to the control shaft 54.

Each of the yoke heads 105 is pivotally mounted on a bracket 96^b and is connected 75 by a link 107 with a lever 108 secured to the vertical shaft 95^b in each of the brackets 96^b. The lower end of each shaft 95^b is provided with a bell-crank lever 109, all of which are interconnected for synchronous 80 movement by links 110—110. The shaft 95^b in the bracket 96^b, lying immediately adjacent the drive shaft 85 of the machine, is provided with a lever 94^b which is adapted to be engaged by a lever 91^b pivoted on the 85 frame of the machine and controlled by the shaft rod 90 from the belt shifter 89.

When the belt shifter 89 is moved to the tight position, the head yokes 105 are turned on their pivots thereby presenting the lower 90 arm 105^a of each yoke head in a position to be engaged by the lower edge 106^a of the arrow head 106 when the machine is set in motion and the annular casing revolving with the head of the machine moves in the 95 direction indicated by the arrow 106, Fig. 16. Engagement between the edge 106^a and the arm 105^a turns the control shaft 54 in a clockwise direction for the purposes above described. Movement of the control shaft 100 54 in a counter-clockwise direction is effected by the movement of the belt shifter to the loose position, a spring 112 turning the vertical shafts 95^b when the lever 91^b moves away from the lever 94^b.

In Figs. 17 and 18, I have shown a modified form of the invention which combines the step ring feature shown in Figs. 8, 9, 10 and 11 with the arrow head feature shown in Figs. 14, 15 and 16, the arrow 110 heads 116 secured to short spindles 117, rotatably mounted in bearings 118 formed on the fixed ring 74^a. Each of the spindles 117 is provided with a crank 119 adapted to engage a formed projection 120 in the movable 115 ring 73^a. The control shaft 54 is provided with a crank 70^a adapted to engage a forked projection 72^a on the ring 73^a. The operation of this form of the invention is obvious in view of the description of the combined 120 forms above referred to, the only difference being that in this instance but one bracket 96^c and one yoke head 105^c is employed, the arrow heads 116 passing this yoke in rapid succession.

There are occasions when the belt shifter is operated to stop the knitting machine by other than manual power, but in a manner similar to the manual operation, being effected by what is known to the art as an 130

automatic needle protector. This needle protector automatically stops the machine by operating the belt shifter in a manner identical with the manual operation thereof 5 when a needle is broken, bent or otherwise defective. This needle protector is provided on many of the knitting machines in use at the present time, but as it forms no part of the present invention, and merely operates 10 the belt shifter in a manner identical with the manual operation thereof, it has not been shown and in the claims where manual operation of the belt shifter is mentioned it will be understood that this operation 15 may be effected either by purely manual means or by means of the automatic needle protector.

I claim:

1. In combination with a stop motion for 20 knitting machines of the type wherein a shifting of the belt to the loose pulley to stop the machine actuates the trip mechanism of the stop motion; means for restraining the trip mechanism of the stop motion 25 from actuating in a manner to trip the stop motion, when the belt shifter of the knitting machine is manually moved to a position to stop the knitting machine.
2. In combination with a stop motion for 30 knitting machines of the type wherein a shifting of the belt to the loose pulley to stop the machine actuates the trip mechanism of the stop motion; means for restraining the trip mechanism of the stop motion 35 from actuating in a manner to trip the stop motion, when the belt shifter of the knitting machine is manually moved to a position to stop the knitting machine; and means operable by said belt shifter for controlling said 40 restraining means.
3. In combination with a stop motion for a knitting machine of the rotating head type, wherein a shifting of the belt to the loose pulley to stop the machine actuates the trip mechanism of the stop motion and 45 wherein the controlling mechanism of the stop motion rotates with said rotating head; means for restraining the trip mechanism of the stop motion from actuating in a manner 50 to trip the stop motion, when the belt shifter of the knitting machine is manually moved to a position to stop the knitting machine; and means secured to the stationary portion of the knitting machine and co-operating 55 with elements of the rotating portion of the stop motion and operable by said belt shifter for controlling the actuation of the said restraining means.
4. In combination with a knitting machine 60 stop motion comprising trip mechanism for automatically moving the belt shifter of the knitting machine to a position to stop the machine when a thread becomes broken, strained or slack, including trip mechanism 65 having drop wires each movable to a thread- 70 ing position, a running position and a trip position and a trip ring operable by said drop wires and movable to like positions thereby and a retaining hook for engaging and holding said ring in the threading position after the trip mechanism has been operated thereby to automatically move the belt shifter to the stop position; means for restraining the trip mechanism from actuation when the said belt shifter is manually moved 75 to its stop position.
5. In combination with a knitting machine 80 stop motion comprising trip mechanism for automatically moving the belt shifter of the knitting machine to a position to stop the machine when a thread becomes broken, strained or slack, including trip mechanism 85 having drop wires each movable to a threading position, a running position and a trip position and a trip ring operable by said drop wires and movable to like positions thereby and a retaining hook for engaging and holding said ring in the threaded position after the trip mechanism has been operated thereby to automatically move the belt 90 shifter to the stop position; means for restraining the said ring from movement into its trip position when the said belt shifter has been manually moved to its stop position.
6. In combination with a knitting machine 95 stop motion comprising trip mechanism for automatically moving the belt shifter of the knitting machine to a position to stop the machine when a thread becomes broken, strained or slack, including trip mechanism 100 having drop wires each movable to a threading position, a running position and a trip position and a trip ring operable by said drop wires and movable to like positions thereby and a retaining hook for engaging 105 and holding said ring in the threaded position after the trip mechanism has been operated thereby to automatically move the belt shifter to the stop position; means for restraining the trip mechanism from actuation when the said belt shifter is manually moved to its stop position; and means operable by 110 said belt shifter for controlling the actuation of said restraining means.
7. In combination with a knitting machine 115 of the rotating head type and a stop motion therefor substantially as described, said stop motion comprising trip mechanism rotatable with said knitting head, actuation of which causes the belt shifter of the machine to be automatically moved to a position to stop the machine when a thread becomes broken, strained or slack; means rotatable with said trip mechanism and co-operating therewith to restrain said trip mechanism from actuation when said belt shifter is manually moved to a position to stop the knitting machine; and stationary means operable by said belt shifter for controlling said restraining 120 means.
8. In combination with a knitting machine 125 stop motion comprising trip mechanism for automatically moving the belt shifter of the knitting machine to a position to stop the machine when a thread becomes broken, strained or slack, including trip mechanism 130 having drop wires each movable to a thread-

8. In combination with a knitting machine of the rotating head type and a stop motion therefor substantially as described, said stop motion comprising trip mechanism rotatable with said knitting head, actuation of which causes the belt shifter of the machine to be automatically moved to a position to stop the machine when a thread becomes broken, strained or slack, said trip mechanism including drop-wires movable to a threading position, a running position or a trip position, a trip ring co-operating with said drop wires and movable to the same relative positions as said drop wires and a retaining hook adapted to engage said trip ring after it has been moved to its threading position subsequent to the tripping actuation of said trip mechanism; a restraining hook adapted to engage said trip ring to prevent actuation of the said trip mechanism thereby when said belt shifter is moved manually to a position to stop the knitting machine.
9. In combination with a knitting machine of the rotating head type and a stop motion therefor substantially as described, said stop motion comprising trip mechanism rotatable with said knitting head, actuation of which causes the belt shifter of the machine to be automatically moved to a position to stop the machine when a thread becomes broken, strained or slack, said trip mechanism including drop-wires movable to a threading position, a running position or a trip position, a trip ring co-operating with said drop wires and movable to the same relative positions as said drop wires and a retaining hook adapted to engage said trip ring after it has been moved to its threading position subsequent to the tripping actuation of said trip mechanism; a restraining hook adapted to engage said trip ring to prevent actuation of the said trip mechanism thereby when said belt shifter is moved manually to a position to stop the knitting machine; a control shaft, for said retaining hook and said restraining hook rotatable bodily with said trip mechanism; an oscillating ring for operating said control shaft; a step ring secured to said rotating head adapted to support said oscillating ring; levers pivoted to said step ring and engaging said oscillating ring; and a stationary pivoted shoe adapted to engage said levers, operable by said belt shifter.
10. In combination with a knitting machine of the rotating head type and a stop motion therefor substantially as described, said stop motion comprising trip mechanism rotatable with said knitting head, actuation of which causes the belt shifter of the machine to be automatically moved to a position to stop the machine when a thread becomes broken, strained or slack, said trip mechanism including drop-wires movable to a threading position, a running position or a trip position, a trip ring co-operating with said drop wires and movable to the same relative positions as said drop wires and a retaining hook adapted to engage said trip ring after it has been moved to its threading
- position subsequent to the tripping actuation of said trip mechanism; a restraining hook adapted to engage said trip ring to prevent actuation of the said trip mechanism thereby when said belt shifter is moved manually to a position to stop the knitting machine; a control shaft, for said retaining hook and said restraining hook rotatable bodily with said trip mechanism; an oscillating ring for operating said control shaft; a step ring secured to said rotating head adapted to support said oscillating ring; levers pivoted to said step ring and engaging said oscillating ring; and a stationary pivoted shoe adapted to engage said levers, operable by said belt shifter.
11. In combination with a knitting machine of the rotating head type and a stop motion therefor substantially as described, said stop motion comprising trip mechanism rotatable with said knitting head, actuation of which causes the belt shifter of the machine to be automatically moved to a position to stop the machine when a thread becomes broken, strained or slack, said trip mechanism including drop-wires movable to a threading position, a running position or a trip position, a trip ring co-operating with said drop wires and movable to the same relative positions as said drop wires and a retaining hook adapted to engage said trip ring after it has been moved to its threading position subsequent to the tripping actuation of said trip mechanism; a restraining hook adapted to engage said trip ring to prevent actuation of the said trip mechanism thereby when said belt shifter is moved manually to a position to stop the knitting machine; a control shaft, for said retaining hook and said restraining hook rotatable bodily with said trip mechanism; an oscillating ring for operating said control shaft; a step ring secured to said rotating head adapted to support said oscillating ring; levers pivoted to said step ring and engaging said oscillating ring; and a stationary pivoted shoe adapted to engage said levers, operable by said belt shifter.
12. In combination with a knitting machine of the rotating head type and a stop motion therefor substantially as described, said stop motion comprising trip mechanism rotatable with said knitting head, actuation of which causes the belt shifter of the machine to be automatically moved to a position to stop the machine when a thread becomes broken, strained or slack, said trip mechanism including drop-wires movable to a threading position, a running position or a trip position, a trip ring co-operating with said drop wires and movable to the same relative positions as said drop wires and a retaining hook adapted to engage said trip ring after it has been moved to its threading position subsequent to the tripping actuation of said trip mechanism; a restraining hook

adapted to engage said trip ring to prevent actuation of the said trip mechanism thereby when said belt shifter is moved manually to a position to stop the knitting machine; a control shaft for said retaining hook and said restraining hook rotatable bodily with said trip mechanism; an oscillating ring for operating said control shaft; a step ring secured to said rotating head adapted to support said oscillating ring; levers pivoted to said step ring and engaging said oscillating ring; a stationary pivoted shoe operable by said belt shifter adapted to engage said levers and thereby rotate said control shaft in one direction; and resilient means for rotating said control shaft in the opposite direction.

ALFRED CRAWFORD.
